UNITED STATES PATENT OFFICE

WILLIAM E. OSHEI, OF BUFFALO, NEW YORK

DESIGN FOR AN OIL-CHANGE INDICATOR FOR MOTOR VEHICLES

Application filed January 4, 1930. Serial No. 34,019. Term of patent 3½ years.

To all whom it may concern:

Be it known that I, WILLIAM E. OSHEI, a citizen of the United States, residing at Buffalo, in the county of Erie and State of New York, have invented a new, original, and ornamental Design for Oil-Change Indicator for Motor Vehicles, of which the following is a specification, reference being had to the accompanying drawing, forming part thereof.

Fig. 1 is a front elevation of the indicator showing the new design.

Fig. 2 is a plan view of the same.

I claim:

The ornamental design for an oil change indicator for motor vehicles, as shown.

WILLIAM E. OSHEI.
